UNITED STATES PATENT OFFICE

124,779

DESIGN FOR AN AUTOMOBILE

Willard L. Greene, Cincinnati, Ohio

Application September 14, 1940, Serial No. 95,046

Term of patent 3½ years

To all whom it may concern:

Be it known that I, Willard L. Greene, a citizen of the United States and a resident of Cincinnati, in the county of Hamilton and State of Ohio, have invented a new, original, and ornamental Design for an Automobile, of which the following is a specification, reference being had to the accompanying drawing, forming part thereof.

Figure I is a side elevational view of an automobile showing my new design with the front portion illustrated in full lines, and illustrating the rear end and intermediate portions of the automobile in dotted lines.

Figure II is a three-quarter front perspective

view of an automobile showing my new design with the front portion illustrated in full lines, and illustrating the rear end and intermediate portions of the automobile in dotted lines.

Figure III is a front end view of an automobile showing my new design.

The dominant feature of my new design comprises the appearance of the front end portion, particularly the single, horizontally arranged head light, as illustrated in full lines.

I claim:

The ornamental design for an automobile, substantially as shown and described.

WILLARD L. GROENE.
